SWITCHING SCHEME

Hubert R. Shaw, Bridgeport, Conn., assignor to
General Electric Company, a corporation of New
York

Application November 2, 1938, Serial No. 238,415

3 Claims. (Cl. 179—1)

My invention relates to communication systems and particularly to such systems as are used for interoffice communication, public address, etc.

In such systems commonly an amplifier is employed which is alternately reversed in its connections to amplify signals from either of two signal stations and to transmit the amplified signals to the other station.

One object of my invention is to provide such a system having means to prevent regeneration of said amplifier due to any coupling between conductors which are connected respectively to the input and output of said amplifier and which may be close to each other as in twisted lines in any practical installation of the equipment.

Another object of my invention relates to such a system employing such means for preventing regeneration in which means are also employed to prevent extraneous noises at the location of any station from being reproduced at a different station when the system is not in use.

The novel features which I believe to be characteristic of my invention are set forth with particularity in the appended claims. My invention itself, however, both as to its organization and method of operation together with further objects and advantages thereof may best be understood by reference to the following description taken in connection with the accompanying drawing in which the single figure represents an embodiment of my invention.

Referring to the drawing I have shown at 1 a central station, at 2, 3, 4, and 5 a number of outlying stations, and at 6 an amplifier, together with means whereby the operator at station 1 may call any of stations 2, 3, 4, and 5 through said amplifier, and whereby he may be called through said amplifier from any of said stations 2, 3, 4, and 5. This means comprises a plurality of switches including a talk-listen switch 7 located at the central station 1 and also a talk-listen switch 8 located at each of the other stations.

The talk-listen switch 7 at the central station 1 comprises a plurality of stationary contacts 9, 10, 11, 12, 13, 14, and 15, mounted upon a stator 16, and a plurality of conducting segments 20, 21, and 22, mounted upon a rotor 23. This rotor may be a suitable non-conducting disk upon which the segments are mounted and which is rotated about an axis by means of a handle 24 movable between two positions as shown in the drawing. The talk-listen switches 8 of the stations 2, 3, 4, and 5 are simple double-throw switches which are arranged to connect the loud speaker between the common

conductor 27 and either of two conductors 25 or 26 extending to each station.

The stations 1, 2, 3, 4, and 5 may all comprise simple loud speakers preferably of the dynamic type having permanent magnets or field coils. One side of all these loud speakers is connected to a common, or ground conductor 27, and to one side of the input transformer 28 of amplifier 6 and to one side of the output transformer 29, of amplifier 6, the respective switches 7 and 8 being shown on the opposite side of the various circuits.

At 30 is a selector switch which may be of the ordinary so-called Yaxley construction comprising a plurality of wafers, each wafer having a number of stationary contacts and rotating conducting segments cooperating therewith, one wafer 31 being provided for conductors 25 extending to the different outlying stations, and the other wafer 32 being provided for conductors 26 extending to the different outlying stations. By means of these switches as will presently be explained, any one, or all of the outlying stations 2, 3, 4, and 5 may be connected by the operator at station 1 for communication with the central station 1.

The rotor of the switch 30 is also provided with a member 35 which in one extreme position of the switch engages a switch member 36 arranged in the power supply circuit 37 for the amplifier 6, thereby interrupting the supply of power to that amplifier.

Having thus indicated the general nature of the equipment to which my invention pertains I shall now describe the various circuits employed in greater detail by reference to its operation. It will be observed that with the switches in the position shown the loud speaker 1 is connected directly across the secondary winding of transformer 29; this circuit comprises loud speaker 1, stationary contact 15, segment 22, stationary contact 14, secondary winding of transformer 29 and ground, or common conductor 27, back to the loud speaker.

It will also be observed that with the switches in the position shown, although station 1 is connected for listening, no currents generated by reason of noise in the localities of stations 2, 3, 4, and 5 or otherwise, are transmitted to the input of the amplifier for amplification thereby, and hence produce no disturbance in the station 1. This is by reason of the fact that the circuit of conductors 26 for stations 3, 4, and 5 are all open at segment 38 of wafer 32 of switch 30, and the circuit of conductor 26 for station 2 is also open at segment 21 of switch 1.

With the switch 30 in the position shown the operator at stations 3, 4, and 5 is incapable of calling station 1. The operator at station 2, however, may call station 1 by moving switch 8 to the 5 left and speaking into his loud speaker. The circuit for the loud speaker of station 2 extends from ground through ground conductor 27, loud speaker 2, switch 8 in its left-hand position, conductor 25 of station 2, segment 39 of switch 30, contact 10 40, conductor 41, stationary contact 11, segment 20, and stationary contact 10 of switch 7, conductor 42 and primary winding of input transformer 28 to ground. These currents are of course amplified by amplifier 6 and supplied to 15 station 1.

The operator at station 1 may now answer the call by operating his switch 7 to the opposite, or talk, position which is the dotted line position of handle 24 shown in the drawing. In this position 20 the conducting segments 20, 21, and 22 are rotated counterclockwise by the distance equal to the space between two adjacent contacts. In this position conductor 43 of station 1 is connected through stationary contacts 14, segment 22 and 25 stationary contact 13 to conductor 41 and thence through stationary contact 40, segment 39 and stationary contact 44 of switch 31 to conductor 25 of station 2 with which conductor switch 8 is now in engagement. The output currents from 30 the amplifier 6 are thus transmitted to the loud speaker 2. At the same time loud speaker 1 is connected to the input of the amplifier through stationary contact 9, segment 20 and contact 10 of switch 7, and conductor 42 to the primary winding of transformer 28. Thus any words spoken by the operator at station 1 are heard by the operator at station 2.

During the subsequent conversation it is necessary for the operator at station 1 to alternate 40 switch 7 between its talk and listen positions as he alternately talks and listens. The switch 8 in the outlying station, however, may remain in its left-hand position throughout the conversation.

If, with the equipment in the position shown 45 in the drawing, the operator at station 1 desires to call any of the stations 2, 3, 4, and 5 he operates the switch 30 to the position corresponding to the station to be called and the switch 24 to the talk position and then speaks into the loud 50 speaker. His loud speaker is then connected to the input of the transformer through stationary contacts 9 and 10 of switch 7. The output of the amplifier is connected through conductor 43, stationary contact 14, segment 22, and contact 13 55 of switch 7, thence through stationary contact 11, segment 21 and contact 12 of switch 7, conductor 45, stationary contact 46 and segment 47 and that one of the other stationary contacts with which it may be in engagement of switch 60 32 to conductor 26 of the called station. Thus the words spoken into the loud speaker 1 are heard by the operator at the called station.

The operator at the called station then moves his switch 8 to the left and answers into his 65 microphone.

It will be seen that the loud speaker at station 1 is connected to conductor 43 for listening and to conductor 42 for talking and that the loud speakers at stations 2, 3, 4, and 5 may be connected to either conductors 25 or 26 for listening 70 but must be connected to conductor 25 for talking.

Thus any station 2, 3, 4, or 5 may call station 1 by movement of its switch 8 to the left, and similarly, station 1 may call any station 2, 3, 4, or 5

by moving its switch 7 to the talk position. In this position the subsequent conversation may be carried on without further manipulation of switch 8.

All of stations 2, 3, 4, and 5 are connected to 5 the system by means of switches 31 and 32 in exactly the same way as that shown on the drawing for station 2 when switches 31 and 32 are moved in the counterclockwise direction to corresponding positions. If this switch be moved in the 10 counterclockwise direction through the space of one contact then all of these stations are connected together; that is, all of the conductors 25 of the various stations are connected together by segment 49 of switch 31 and all conductors 26 15 are connected together by segment 38 of switch 32, all of conductors 25 are then also connected to switch 7 through segment 39, stationary contact 40, and conductor 41 and similarly all of conductors 26 are connected to switch 7 through 20 segment 47, contact 46 and conductor 45. Thus, if the operator at station 1 operates his switch to the talk position and speaks into the loud speaker his words are reproduced at all of the outlying stations. If all of the operators at the outlying 25 stations operate their switches to the left they may all talk with the central station as in conference telephony.

The conductors 25, 26, and 27 which extend to the outlying stations may, of course, be twisted 30 together or in cable form. With the circuits arranged as described, no regeneration of the amplifier is produced by reason of conductors connected to the input and outlet circuits but which are twisted together, or lie in proximity to each 35 other, throughout any considerable length extending to a distant station. The switch 7 and the conductors 42 and 43 as well as loud speaker 1 may all be arranged within the housing of amplifier 6 and thus there is no appreciable coupling 40 between the output and input circuit of the amplifier in these conductors.

All of conductors 25 are connected to conductor 27 at their remote ends by resistors 45. These resistors have such a value as to load the line 45 and reduce pick up of noise and disturbing voltages therein.

While I have shown particular embodiments of my invention it will, of course, be understood that I do not wish to be limited thereto, since different arrangements both in the circuit arrangement and the instrumentalities employed may be made without departing from the spirit and scope of my invention. I, therefore, contemplate by the appended claims to cover any such 55 modifications as fall within the true spirit and scope of my invention.

What I claim as new and desire to secure by Letters Patent of the United States is:

1. In combination, a pair of intercommunicating stations, an amplifier at one of said stations, means to connect said amplifier for transmission from either of said stations to the other, said means comprising double-throw switches in each station, each of said switches being arranged in one position to connect the respective station to one conductor for talking thereover and in the other position to connect it to another conductor for listening thereover, said conductors connecting said amplifier with said switches, and switching means to isolate any conductor extending between said stations connected to the input of said amplifier from any conductor extending between said stations connected to the output of said am- 70 75

plifier thereby to avoid feed-back from the output of said amplifier to the input thereof.

2. In combination a pair of intercommunicating stations, an amplifier, common, talk and listen conductors, extending from said amplifier to each of said stations, the listen conductor of one station being connected to the output of said amplifier and the listen conductor of the other station being open circuited at said one station, and the talk conductors being connected to the input of said amplifier, each station being normally connected between the respective common and listen conductors and having switching means to disconnect it therefrom and to connect it between its common and talk conductors, and means in said one station to connect the output of said amplifier to the listen conductor of the other station whereby regeneration of said amplifier is not produced by reason of coupling be-

tween the talk and listen conductors of said other station.

3. In combination a pair of intercommunicating stations, three conductors joining said stations, an amplifier in one of said stations, said one station being normally connected across the output of said amplifier and the other station being normally connected between two of said conductors, one of which is grounded and the other of which is disconnected from said amplifier, means to connect said other station between said grounded conductor and a third of said three conductors, said third conductor being connected to the input of said amplifier, and means at the one station to connect that station across the input to said amplifier and to connect the output of said amplifier to said other of said three conductors. 5 10 15
